UNITED STATES PATENT OFFICE.

HERBERT A. WALLACE, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,231,541.

Specification of Letters Patent. Patented June 26, 1917.

Original application filed November 8, 1913, Serial No. 799,911. Divided and this application filed June 18, 1914. Serial No. 845,765.

To all whom it may concern:

Be it known that I, HERBERT A. WALLACE, a citizen of the United States, residing at New York, in the county of New York and 5 State of New York, have invented certain new and useful Improvements in Railway Signaling, of which the following is a specification.

10 My invention relates to railway signaling systems in which the signals are controlled by track circuits. More particularly my invention relates to signaling for governing traffic in both directions over a stretch of single track.

15 The present application is a division of my pending application, Serial No. 799,911, filed November 8, 1913, for railway signaling systems, which latter is a continuation of my application filed May 28, 1909, Serial 20 No. 498,883.

I will describe one form of signaling system embodying my invention, and will then point out the novel features thereof in claims.

25 The accompanying drawing is a diagrammatic view illustrating a stretch of railway track over which cars or trains travel in both directions and having applied thereto a signaling system embodying my invention.

30 Referring to the drawing, A designates a stretch of railway track over which traffic moves in both directions. As here shown, I provide a track section C—C', which is electrically isolated from the rest of the track 35 by insulated rail joints α . The track section C—C' is provided with a track circuit comprising the rails of the section, two relays R and R', connected with the rails adjacent the ends of the section respectively, and a source 40 of alternating signaling current connected with the rails adjacent the middle of the section. As here shown the source of signaling current is a transformer T, whose secondary is connected with the rails of the section, 45 and whose primary is connected with mains f, f' to which alternating signaling current is supplied from a source F. The track relays R and R' are preferably of a type which will respond to the alternating signaling 50 current but not to direct current, and in the drawing this is indicated in the conventional manner by diagonal lines in the relays.

With an arrangement of track circuit such

as I have just described, that is, with the source of signaling current connected at 55 about the middle of the track circuit and a relay at each end thereof, I have observed in practice that as a car or train enters one end of the track circuit it will open the track relay adjacent that end only and that the 60 track relay at the other end of the track circuit is opened only when the car or train has reached a point at a distance from the point of connection of the signaling current with the track rails, depending upon the length 65 of track circuit. Also, after the car or train has passed about the same distance beyond this point of connection, the relay first 70 opened again closes, the relay at the exit end remaining open, however, until after the car or train leaves the track circuit. In this invention I have taken advantage of the foregoing facts by arranging railway signals to be controlled by relays as hereinafter explained.

75 S designates a signal governing traffic in the direction of arrow 49, which signal is located adjacent the point at which the relay R' is opened by a car or train moving in the direction of arrow 49, and which signal 80 is controlled by relay R'. The circuit for signal S is from one side of battery P' through contact 1 of relay R', wire 2, mechanism of signal S, wire 3, common return wire O to battery P'. Another signal, S', 85 governing traffic in the direction of arrow 50, is located adjacent the point at which relay R is opened by a car or train moving in such direction, and is controlled by relay R. The circuit for signal S' is from one 90 side of battery P through contact of relay R, wire 4, mechanism of signal S', wire 5, common return wire O to battery P.

The operation of the system is as follows: As a train or car moving in the direction of 95 arrow 49 enters section C—C', relay R will be deenergized, thereby causing signal S' to indicate danger or stop. Signal S' will remain in the danger position until after the car or train passes it, as relay R will not 100 pick up until the car or train has passed beyond that point. As the train passes signal S, this signal will change to danger indication, since when the train passes this point relay R' will be deenergized, thereby 105 opening the circuit for signal S at contact 1.

of relay R'. Signal S will not change to the clear position until relay R' closes, that is, until the train has passed out of the track section C—C'. The operation of the apparatus during the passage of a car or train in the direction of arrow 50 will be similar to that just explained. The point at which a car or train moving through the track section C—C' will cause the track relay at 5 the exit end of the section to open is somewhat variable due to conditions of the track-way as to moisture, etc. The average location of this point is indicated on the drawing by the line designated—"point at which 10 relay R (R') opens." In order to prevent a signal from changing to danger before it is reached by an approaching train, the signal should be located at least as far in the rear of the point of connection of the transition 15 former with the track as the extreme position in the rear of that point at which a car or train will under any circumstances cause the relay at the exit end of the section to open. In accordance with the usual practice, 20 the signal is preferably located even a short distance in the rear of this extreme position, so that the signal does not change to danger until after it has been passed by the front end of a car or train. This location 25 of the signals is indicated on the drawing. My invention provides a preliminary section extending from each signal S and S' to the adjacent end of the section C—C', and hence it is impossible to bring two cars 30 or trains together in the space between the signals. A system of this type is particularly adapted for the protection of a single track through tunnels over bridges, etc. By means of my present invention, I employ 35 one track circuit to perform functions for which three track circuits have heretofore been required.

Although I have not herein shown or described any means for supplying motive power to the cars or trains traveling along the railway, it is understood that signaling systems embodying my invention, are equally well adapted for use on railways using any form of motive power, such for example as 45 steam, electricity, or compressed air. Nor do I wish to limit myself to alternating signaling current in the track circuits, for the reason that direct signaling current may be used instead, the arrangement of track 50 relays, source of signaling current, and signals remaining the same.

Although I have herein shown and described only one form of signaling system embodying my invention, it is understood 55 that various changes and modifications may be made therein within the scope of the

appended claims, without departing from the spirit and scope of my invention.

Having thus described my invention, what I claim is:

1. In combination, a section of railway track over which traffic moves in both directions, a source of signaling current connected with the track rails adjacent the middle of the section, two track relays one connected with the track rails adjacent each end of the section, a signal located in advance of one end of the section and controlled by the relay at the other end, said signal being located adjacent the point at 70 which a car or train passing through the section from the first-mentioned end opens the relay at the last-mentioned end, and a second signal located between the source of current and the last-mentioned end and controlled by the relay at the first-mentioned end, said second signal being located adjacent the point at which a car or train passing through the section toward the first-mentioned end opens the first-mentioned 75 relay.

2. In combination, a section of railway track over which traffic moves in both directions, a source of signaling current connected with the track rails adjacent the middle of the section, two track relays one connected with the track rails adjacent each end of the section, and two signals located on opposite sides respectively of the point of connection of the source with the track 90 rails and each controlled by the track relay on the other side of said point, each signal being located adjacent the point at which the relay which controls it is opened by a car or train passing through the section toward 95 the relay.

3. In combination, a section of railway track over which traffic moves in both directions, a source of alternating signaling current connected with the track rails adjacent the middle of the section, two track relays one adjacent each end of the section, and two signals located on opposite sides respectively of the point of connection of the source with the track rails and each controlled by the track relay on the other side of said point, each signal being located adjacent the point at which the relay which controls it is opened by a car or train passing through the section toward the relay. 110

In testimony whereof I affix my signature in presence of two witnesses.

HERBERT A. WALLACE.
